TRUNKING SYSTEM FOR TELEPHONE-EXCHANGES.

1,133,879.

Specification of Letters Patent. Patented May 11, 1915.

Application filed September 8, 1909. Serial No. 513,769.

To all whom it may concern:

Be it known that I, FRANK R. McBERTY, citizen of the United States, residing at New Rochelle, in the county of Westchester and State of New York, have invented a certain new and useful Improvement in Trunking Systems for Telephone-Exchanges, of which the following is a full, clear, concise, and exact description.

10 My invention relates to telephone exchange systems and particularly to a system of trunking in an automatic or semi-automatic exchange. Its object is in general to improve the condition of the connecting circuits with respect to their use in transmitting telephonic currents.

Other objects are to control the operation of signals and to bring about disconnection of telephone lines connected over circuits 20 including a trunk line, and to accomplish these results without flow of current in the trunk line, and preferably also without a connection from any part thereof to ground or to other circuits during the period of use 25 of the lines for telephonic communication. The freedom from flow of current in the trunk line is advantageous because, among other reasons the presence of current through the various contacts of selectors or other 30 switch mechanisms is liable to cause noise in the telephone circuits. The absence of ground or other connections to the trunk circuit makes it more easily balanced with respect to induced currents from other 35 circuits.

Some of the features of a semi-automatic telephone exchange system to which my invention has been applied may be described briefly as follows: The telephone lines of 40 various subscriber's stations extend some to one and some to another or other distant central offices and there terminate in suitable connecting switches such as spring jack switches at A boards and automatic switches 45 or selectors at B boards. At each office, connecting circuits are provided at the A boards and these may have plugs adapted to be inserted in the springjacks. These connecting circuits lead to the brushes of selectors, the 50 fixed terminals of which are connected through interoffice trunk lines to the brushes of other selectors at the B boards of the distant offices. The terminals of the last mentioned selectors may lead either directly to 55 the telephone lines, or, as in large systems,

through office trunk lines and other selectors and thence to the telephone lines. It will be sufficient, for the purpose of describing my invention, to consider a single such inter-office trunk line and two telephone lines 60 adapted to be connected therethrough for telephonic communication, together with the apparatus and circuits involved in signaling over the trunk lines and in the control of the disconnection of the lines at the termination 65 of the conversation.

It is desirable, on account of the cost of line wires, that each interoffice trunk line comprise but two wires between the offices, these wires serving the purposes of telephonic transmission between the connected telephone lines, of signaling and of controlling the connecting switches or selectors. It is also desirable, and it is customary in such trunking systems, to supply current to 70 the connected telephone lines by two batteries, one at the A board for the calling line, and the other at the B board for the called line. The first mentioned battery is included in the connecting circuit and the 75 other in that part of the trunk circuit which leads to the called line. The other part of the trunk circuit forms an intermediate and separate conductive circuit extending from the A board at one office to the B board of 80 the other office. Repeating coils, or other inductive devices, one located at each end of the trunk circuit serve the purpose of permitting the telephonic currents to be transmitted from one subscriber's line to the 85 trunk circuit, and from the trunk circuit to the other line while conductively separating the line and trunk circuits from each other.

In such a semi-automatic telephone exchange system as the one being considered, 90 an operator is stationed at the A board. Her duties are (1) to make connection with the calling line by inserting the connecting plug in the line springjack when the subscriber calls; (2) to set up on suitable controlling or sending mechanism a condition adapted to cause the automatic switch to pick out and make connection with the line of the desired called subscriber; and (3) when the conversation is completed and the 95 subscribers have hung up their telephones, thereby causing signals to be operated at the A board, to withdraw the plug from the springjack, or to perform some other manual act, thereby causing the selectors to be re- 100 105 110

stored to their normal condition and thus to disconnect the circuit of the telephone lines.

The control of the supervisory or disconnect signal at one end of the trunk line and 5 of the restoring mechanism for the automatic switch at the other end thereof is ordinarily had over circuits including in part at least the wires of the trunk line, and some means is provided to prevent the changes in 10 the circuit of the trunk line when operating the supervisory or disconnect signal from effecting the release of the automatic switch—this in order that the automatic switch shall be wholly under the control of 15 mechanism made operative from the distant end of the trunk line.

According to my invention the changes in the trunk line for purposes of signaling are prevented from effecting the restoration of 20 the automatic switch by means of the following arrangement. The trunk line is closed at both ends; it is provided at the end nearest the automatic switch with switching mechanism adapted to interpose a source 25 of current therein; a device is included in the trunk line responsive to current from said source and adapted to control the restoring mechanism, and means operated in the movement of the switching mechanism 30 is provided to reverse the control of said device over the restoring mechanism. The restoring mechanism is preferably controlled by a magnet and the device in the trunk line for the control thereof is preferably a relay 35 which controls the restoration of the automatic switch by means of a circuit for the restoring magnet. This circuit may be one having two paths adapted to be closed in alternate positions respectively of the ar- 40 ture of the relay and the switching mechanism referred to may have an element adapted in the movement thereof to change the connection of the circuit from one of said paths to the other. The switching 45 mechanism may be controlled by a relay in the called telephone line, which relay is in turn controlled from the substation of the line, in which case the continuity of each of the two paths of the circuit for the restoring 50 magnet is controlled by the relay in the trunk line and by the relay in the telephone line. The device or relay in the trunk line which controls the restoring magnet of the automatic switch may be made operative to 55 effect the restoration of the automatic switch by means of a source of current interposed in the trunk line at the other end thereof by suitable switching mechanism. This last mentioned switching mechanism is prefer- 60 ably arranged to be operated in successive stages to open the trunk line and to interpose therein the last mentioned source of current. The opening of the trunk line operates the controlling device for the restor- 65 ing mechanism when the first mentioned

source of current is included in the trunk line and the closing of the trunk line through the last mentioned source of current causes the response of the controlling device for the restoring magnet when the trunk line 70 is closed without the interposition of the first mentioned source of current.

My invention further provides an arrangement by which a manual switch controlling the continuity of a calling line also controls 75 the operation of the last mentioned switching mechanism to effect the restoration of the automatic switch in the called line, and this switching mechanism may also have an element adapted to effect the restoration of an 80 automatic switch controlling the continuity of the trunk line. The relay in the called telephone line is preferably so arranged that upon the opening of the telephone line at the substation switch it operates the switching 85 mechanism referred to to interpose a source of current in the trunk line to cause the response of the signal at the distant end of the trunk line.

The accompanying drawing shows dia- 90 grammatically that part of the apparatus and circuits of a semi-automatic telephone system which embodies my invention.

In the drawing, 1 and 2 represent calling and called telephone substations, respectively, and 3 and 4 the switches thereof, substation 1 being connected by line wires 5, 6, to a springjack 7 at a switchboard A, and substation 2 being connected by line wires 8, 9, to a pair of fixed terminals 10, 11, of a 100 selector 12 at a switchboard B. A plug 13 of a connecting circuit 14 is shown as inserted in the springjack, this connecting circuit including windings 15, 16, of a repeating coil 17, the opposing windings 18, 105 19, of which lead to a pair of brushes 20, 21 of a selector 22. The circuit from the selector is extended by way of a pair of fixed terminals 23, 24, thereof over trunk line conductors 25, 26, to the windings 27, 28 of a 110 repeating coil 29, the opposing windings 30, 31 of which lead to a pair of brushes 32, 33 of the selector 12.

Between windings 15 and 16 is a bat- 115 tery 34 which supplies current over the calling line 5, 6, to station 1. Windings 18 and 19 are adapted to be connected either through a conductor 35 without the interposition of a source of current or through conductor 36 including a battery 37. The 120 connection through one or the other of these conductors is controlled by a sequence switch 38, which will be described presently.

A local circuit 39 including the winding 125 of a relay 40 is controlled through the sleeve contacts of the plug 13 and springjack 7 so that the relay is energized when the plug is inserted. This relay controls a local circuit 41 which becomes closed when relay 40 is deenergized. Included in the circuit of 130

the trunk line at the A board is a relay 42 controlling in a local circuit a supervisory lamp signal 43, the lamp being lighted when the relay is energized. Interposed serially 5 between windings 27 and 28 of the repeating coil 29 is the winding of a relay 44 and a conductor 45 controlled by front contacts 46, 47 of a relay 48, the circuit being thus closed without the interposition of a source 10 of current when relay 48 is energized. An alternate path between said windings includes a conductor 49 and a battery 50 this path being closed through back contacts 51, 52 when relay 48 is not energized.

15 The circuit of the called line when connected at selector 12 as shown in the drawing, includes battery 50 which is interposed between windings 30 and 31 of the repeating coil 29. A relay 53 controlling the local circuit of relay 48 is included in the circuit and responds to the operation of switch 4 at station 2. Relays 44 and 48 jointly control a local circuit 54 which may be closed through either of two paths, 55, 56 path 55 being 20 operative through back contacts 57, 58 when the relays are deenergized and 56 through front contacts 59, 60 when the relays are energized. This local circuit controls the operation of a sequence switch 61 which will 25 be described presently. A condenser 110 is preferably bridged about the winding of relay 44 and the forward contact 46 of relay 48.

30 Selectors 12 and 22 may have their fixed terminals arranged in curved rows upon a cylindrical frame, as indicated in the drawing, the rows of terminals being adapted to be traversed by the brushes which are rotatably mounted upon spindles 62. The 35 brushes of the selectors are arranged to be rotated by power magnets 63, the revolving pole-pieces 64 of which attract power plates 65 flexibly mounted upon spindles 62 when the magnets are energized.

40 The sequence switches 38 and 61 may be of the same general construction and mode of operation. Only so much of each of them is shown as is helpful in describing the operation of the structure of this invention.

45 Referring to sequence switch 38, 66 to 69 inclusive are cam wheels, preferably of insulating material, mounted on a shaft 70. Each cam wheel engages spring operating switch contacts. At the lower end of the 50 shaft is a circular pole-piece 71 and a power magnet 72, the pole-piece being adapted to be engaged by a rotating armature 73, which is mounted on a continuously rotating shaft 74 by suitable motor mechanism. Contact springs 75 and 76 controlled by cam wheels 66 and 67, respectively, normally rest against contact pieces 77 and 78 forming the terminals of conductor 35. These two cam wheels have raised portions 79, 80 which are adapted, upon the first stage of movement in the 55 rotation of the shaft to move the contact springs into midway position with respect to the opposing contact pieces. The raised portions 81, 82 are adapted upon the second stage to move the springs into contact with contact pieces 83 and 84, which form the terminals of conductor 36. Cam wheel 68 is adapted, when the shaft is rotated after a brief period, to move its contact spring 85 into connection with contact piece 86, connected to ground, while cam wheel 69 is adapted, when the shaft is rotated to maintain the connection between contact spring 87 and contact point 88 until the raised portion 89 engages the spring, when the connection is broken. Similarly cam wheel 90 of sequence switch 61 is adapted, when the shaft 91 is rotated, to cause contact spring 92 to engage contact piece 93, connected to ground, and cam wheel 94 is adapted in the same manner as is cam wheel 69 of sequence switch 38, to cause contact spring 95 to maintain connection with contact piece 96 until the raised portion 97 engages the spring. Pole piece 98, magnet 99, rotating armature 100 and shaft 101 correspond to like parts of the sequence switch 38. In either switch the energization of the power magnet causes the rotating armature to engage the pole piece fixed to the shaft and causes the rotation of the cams. Power magnet 72 is controlled by local circuit 41, which includes contacts 87, 88 and a battery 102. Similarly power magnet 99 is controlled by local circuit 54 which includes contacts 95, 96 and a battery 103. These power magnets may be operated through other circuits than those shown, and I have indicated by branch wires 109 that such other circuits may be provided as required in the system. Power magnets 63 of the 100 selectors are controlled by local circuits 104 and 105 including contacts 85, 86 and 92, 93 and batteries 106 and 107 respectively.

105 The apparatus and circuits are shown in condition for telephonic communication between the substations of two lines, because the operation of the structure so far as this invention is concerned involves principally this condition of the lines and trunk circuit and their disconnection after use by the subscribers. During this period of telephonic communication the talking circuits may be traced as follows: Battery 34 supplies current by way of windings 15 and 16 110 of repeating coil 17 through contacts of the plug 18 and jack 7 and line wires 5, 6 to switch 3 and the telephone instruments at the calling substation 1. Battery 50 likewise supplies current by way of windings 120 30, 31 through brushes 32, 33, terminals 10, 11 of selector 12 and line wires 8, 9, to switch 4 and the telephone instruments at the called substation 2. The intermediate or trunk circuit by which the two telephone 125 130

lines are inductively united is, during this period a closed circuit which includes no source of current and which is entirely free from connection with ground or other circuits. It includes at the A board windings 18, 19, of repeating coil 17, relay 42, contacts 75, 77 and 76, 78 conductor 35 and brushes 20, 21 and terminals 23, 24 of selector 22; and at the B board, windings 27, 28 of repeating coil 29, relay 44, contacts 46 and 47 of relay 48 and conductor 45, the circuit being completed by the trunk line wires 25 and 26, which may extend for a considerable distance between the two boards. To enable these talking circuits to be more readily traced the conductors thereof are shown in heavy lines.

When the subscriber at the called station 2 replaces his telephone on its switch hook, 20 thus opening the circuit of his line at switch 4, relay 53 at the B board is de-energized, causing the opening of the local circuit of relay 48 which in turn operates to open the path in the trunk circuit through conductor 45 and to close the path through conductor 49 and battery 50. The flow of current from this battery over the trunk line causes the energization of relay 42 at the A board and the lighting of the supervisory lamp 43, thus giving the operator a signal that the called subscriber has completed his conversation over the circuit. Relay 48 also opens contact 60 and closes contact 58. Relay 44, however, at the same time receives current from battery 50 and opens contact 57 and closes contact 59. The local circuit 54 of power magnet 99 of the sequence switch 61, therefore, remains open.

In response to the supervisory signal, the 40 operator withdraws plug 13 from spring-jack 7, causing the opening of local circuit 39 of relay 40, which in turn closes the local circuit 41 of power magnet 72 of sequence switch 38. The cam wheels begin 45 to revolve in the direction of the arrow and change circuits as follows: First, the circuit of the trunk line is opened by reason of the raised portions 79 and 80 of cam wheels 66 and 67 lifting springs 75 and 76 from their 50 normal resting contacts 77 and 78, respectively. Second, relay 44 is de-energized and its armature in falling against its back contact 57, closes circuit 54 by way of conductor 55 and back contact 58 of relay 48 to the power magnet 99 of sequence switch 61. Third, power magnet 63 of selector switch 12 is energized over its circuit 105 including contacts 92, 93 and battery 107. The brushes 32, 33 are therefore moved away 60 from the terminals 10, 11 on which they were resting and the circuit of the called line is disconnected. Fourth, the continued movement of sequence switch 38 brings the raised portions 81, 82 of cam wheels 66, 67 65 under springs 75 and 76 respectively, and

closes the trunk circuit again through conductor 36 which includes battery 37. This looping in of battery 37 performs no function under the present assumed condition that the called subscriber had placed his 70 telephone on its switch hook. Fifth, after a brief interval springs 75 and 76 resume their normal position as shown in the drawing and spring 85 is lifted by the raised portion 108 of cam wheel 68, thus closing 75 the circuit of power magnet 63 of selector 22, which moves the brushes 20, 21 away from the terminals 23, 24 and disconnects the trunk line. Sixth, the two sequence switches and the two selectors may 80 continue to advance to any desired positions. As the apparatus is arranged in the drawing, when the raised portions 89 and 97 engage springs 87 and 95, respectively, the circuits of the power magnets 72 and 99 are 85 opened and the movement of the cam wheels stopped. At the same time the circuits of the power magnets 63 may be opened at contacts 85, 86 and 92, 93 respectively.

The operator may disconnect the lines before the called subscriber has hung up his telephone, and the operation in that case is as follows: The plug is removed from the springjack at the A board, and the circuit of power magnet 72 of sequence switch 38 is 90 closed at relay 40 in the manner before described. The opening of the trunk circuit at contact springs 75 and 76 has no effect on the operation of the apparatus at the B board. The continued movement of sequence switch 38, however, loops battery 37 in the trunk circuit and causes a flow of current which energizes relay 44. This relay in turn closes local circuit 54 to power magnet 99 by way of conductor 56 and contact 60 of relay 48. The sequence switch 61 100 closes the circuit of power magnet 63 of selector 12 as before described. It will thus be seen that in either condition of the apparatus at the B board, that is, either while 110 the telephone is off the switch hook at the called subscriber's station, or while it is on the hook, the operator at the A board may bring about disconnection of the lines simply by the removal of the plug from the 115 springjack of the calling line. The circuit of the trunk line between the A and B boards will either be with or without a source of current at the B board, and the sequence switch by successive changes in 120 the condition of the circuit at the A board meets the two conditions and causes disconnection under either one or the other.

Many changes in the details of the apparatus and circuits from those which I have 125 employed to illustrate my invention may be made without departing therefrom. For example, the type of automatic switch may be varied both in construction and in the means of moving the brushes. Other forms 130

of sequence switches might be employed at the A board to change the circuit of the trunk line successively to meet the two conditions at the B board and the sequence switch at the B board might be omitted and the operation of disconnection controlled more directly by apparatus in the trunk line. Other forms of devices for inductively connecting while conductively separating the 10 trunk line and the telephone lines may be substituted for the repeating coils if desired. Some other device than a plug and jack may be employed as the means of connecting the calling line in circuit and the control of the 15 apparatus to cause disconnection may be had by some other act than the removal of a plug from the springjack. Although I have shown several batteries for the sake of clearness in illustrating circuits, it is to 20 be understood that one battery at each switchboard may be employed and would ordinarily be preferred in the place of the several shown.

My invention is not limited to all of the 25 details of the apparatus and circuits which I have described, but is defined in the following claims:

I claim—

1. In a telephone exchange system, the 30 combination with an automatic switching apparatus, a trunk line consisting of a pair of conductors adapted to form part of the talking circuit, and substation lines connected through said automatic switching 35 apparatus and trunk line, of means operable upon the opening of the substation line of the called subscriber for including a source of current in the trunk line, and an electroresponsive circuit-controlling device 40 actuated by current from said source.

2. In a telephone exchange system, the 45 combination with an automatic switching apparatus, a trunk line consisting of a pair of conductors adapted to form part of the talking circuit, and substation lines connected through said automatic switching apparatus and trunk line, of a switch at the 50 substation of the called subscriber adapted to close the line when in use, means at one end of said trunk line operable upon the opening of said switch for including a source of current in the trunk line, and a circuit controlling device at the other end of 55 said trunk line responsive to said source of current.

3. In a telephone exchange system, the 60 combination with an automatic switching apparatus, a trunk line consisting of a pair of conductors adapted to form part of the talking circuit, and substation lines connected through said automatic switching apparatus and trunk line, of a connecting 65 switch included in the circuit of the called substation line, means operable upon the opening of said switch for including a

source of current in the trunk line, and a signaling device in the trunk line responsive to said source of current.

4. In a telephone exchange system, the combination with an automatic switching 70 apparatus, a trunk line consisting of a pair of conductors adapted to form part of the talking circuit, and substation lines physically disconnected from but inductively connected to said trunk line, an automatic 75 switching apparatus uniting said substation line to said inductive connection, of a plug and jack switch included in the circuit of one of said substation lines, means operable upon the removal of the plug for including 80 a source of current in the trunk line, and an electroresponsive circuit-controlling device actuated by current from said source.

5. In a telephone exchange system, the combination with an automatic switching 85 apparatus, a trunk line consisting of a pair of conductors adapted to form part of the talking circuit and substation lines connected through said automatic switching apparatus and trunk line, of a connecting 90 switch included in the circuit of one of said substation lines, means at one end of said trunk line operable upon the opening of said switch adapted in successive stages to open said trunk line and to interpose therein 95 a source of current, and a circuit controlling device at the other end of said trunk line responsive to said source of current.

6. In a telephone exchange system, the combination with an automatic switching 100 apparatus, a closed trunk line consisting of a pair of conductors adapted to form part of the talking circuit and a substation line physically disconnected from but inductively connected to said trunk line, and automatic 105 switching apparatus uniting said substation line to said inductive connection, of restoring mechanism for said automatic switching apparatus and means adapted to include a source of current in the trunk line to effect 110 the operation of said restoring mechanism.

7. In a telephone exchange system, the combination with an automatic switching 115 apparatus, a closed trunk line consisting of a pair of conductors adapted to form part 120 of the talking circuit and substation lines physically disconnected from but inductively connected to said trunk line, one of said substation lines being connected to the inductive connection through said automatic switching mechanism, of restoring mechanism for 125 said automatic switching apparatus and means operable when the circuit of the other of said substation lines is open for including a source of current in the trunk line to effect the operation of said restoring mechanism.

8. In a telephone exchange system, the combination with an automatic switching 130 apparatus, a trunk line and a called substation line connected to said trunk line by 135

said automatic switching apparatus, of a signal device in the trunk line and means operable upon the opening of said substation line for including a source of current in the trunk line to effect the operation of said signal device.

9. In a telephone exchange system, the combination with an automatic switching apparatus, a trunk line and substation lines connected through said automatic switching apparatus and trunk line, of restoring mechanism for said automatic switching apparatus, means operable when the circuit of one of the substation lines is open for including a source of current in the trunk line to effect the operation of said restoring mechanism, a signal device in the trunk line and means operable upon the opening of the other of said substation lines for including a source of current in the trunk line to effect the operation of said signal device.

10. In a telephone exchange system, the combination with an automatic switching apparatus, restoring mechanism therefor, a trunk line and substation lines connected through said switching apparatus and trunk line, of means operable when the circuit of one of said substation lines is open for including a source of current in the trunk line to effect the operation of said restoring mechanism, means operable upon the opening of the other of said substation lines for including a source of current in the trunk line and means for preventing the last mentioned source of current from effecting the operation of said restoring mechanism.

11. In a telephone exchange system, the combination with an automatic switch and restoring mechanism therefor, of a trunk line, a source of current, switching mechanism adapted to interpose said source of current in the trunk line, controlling means for said restoring mechanism responsive to current in the trunk line, and means for changing said controlling means to reverse the mode of control thereof over said restoring mechanism.

12. In a telephone exchange system, the combination with an automatic switch and restoring mechanism therefor, of a trunk line closed at one end, a source of current at the other end thereof, switching mechanism adapted to interpose said source of current in the trunk line, controlling means for said restoring mechanism responsive to current in the trunk line, and means operating in the movement of said switching mechanism arranged to change said controlling means to reverse the mode of control thereof over said restoring mechanism.

13. In a telephone exchange system, the combination with an automatic switch and a restoring magnet therefor, of a trunk line closed at one end, a source of current at the

other end thereof, switching mechanism adapted to interpose said source of current in the trunk line, a relay included in the trunk line and responsive to said source, a circuit for said restoring magnet controlled by said relay, and means operated in the movement of said switching mechanism adapted to change said circuit to reverse the mode of control of said relay over said restoring magnet.

14. In a telephone exchange system, the combination with an automatic switch and a restoring magnet therefor, of a trunk line, a source of current, switching mechanism adapted to interpose said source of current in the trunk line, a relay included in the trunk line and responsive to said source of current, and a circuit for said restoring magnet having two paths adapted to be closed in alternate positions, respectively, of the armature of said relay, said switching mechanism having an element adapted in the movement thereof to change the connection of said circuit from one of said paths to the other.

15. In a telephone exchange system, the combination with an automatic switch and a restoring magnet therefor, of a trunk line, a source of current, a telephone line and a relay included therein controlled from the substation thereof, switching mechanism operated under the control of said relay and adapted to interpose said source of current in the trunk line, a relay in the trunk line responsive to said source of current, a circuit for said restoring magnet having two paths, the continuity of each of which is controlled by both of said relays.

16. In a telephone exchange system, the combination with an automatic switch and restoring mechanism therefor, of a trunk line, a source of current, switching mechanism adapted to interpose said source of current in the trunk line, controlling means for said restoring mechanism responsive to current in the trunk line, means for changing said controlling means to reverse the mode of control thereof over said restoring mechanism and a signal device in the trunk line responsive to said source of current.

17. In a telephone exchange system, the combination with an automatic switch and a restoring magnet therefor, of a trunk line closed at both ends, and having at one end a source of current, a telephone line, a relay responsive to current in said telephone line, switching mechanism under the control of said relay and adapted to interpose said source of current in the trunk line, a relay included in the trunk line and responsive to said source of current, a signal device in the trunk line at the other end thereof, and a circuit for said restoring magnet having two paths the continuity of each of which is controlled by both of said relays.

18. In a telephone exchange system, the combination with an automatic switch and restoring mechanism therefor, of a trunk line consisting of a pair of conductors 5 adapted to form part of the talking circuit, a source of current, switching mechanism adapted to interpose said source of current in series in the trunk line and a device in the trunk line responsive to said source of 10 current and adapted to effect the operation of said restoring mechanism.
19. In a telephone exchange system, the combination with an automatic switch and restoring mechanism therefor, of a trunk line closed at both ends, a source of current 15 at one end, switching mechanism adapted to interpose said source of current in the trunk line, a device in the trunk line at the other end thereof responsive to said source 20 of current and adapted to effect the operation of said restoring mechanism.
20. In a telephone exchange system, the combination with an automatic switch and a restoring magnet therefor, of a trunk line 25 closed at both ends, a source of current, switching mechanism adapted to interpose said source of current in the trunk line at one end thereof, a relay in the trunk line at the other end thereof, a second switching 30 mechanism adapted to control the circuit of said trunk line and a local circuit for said restoring magnet controlled jointly by said relay and an element of said last mentioned switching mechanism.
21. In a telephone exchange system, the combination with an automatic switch and restoring mechanism therefor, of a trunk line, a source of current and switching mechanism adapted to interpose said source of 40 current in the trunk line at one end thereof, controlling means for said restoring mechanism responsive to current in the trunk line, means operating in the movement of said 45 switching mechanism adapted to change said controlling means to reverse the mode of control thereof over said restoring mechanism, and a source of current and switching mechanism at the other end of said trunk line, the last mentioned switching mechanism being 50 adapted in successive stages to open the trunk line and to interpose therein the last mentioned source of current.
22. In a telephone exchange system, the combination with an automatic switch and 55 a restoring magnet therefor, of a trunk line, a source of current at one end thereof, switching mechanism adapted to interpose said source of current in the trunk line and a relay in the trunk line responsive to said 60 source of current, a telephone line, a relay responsive to current therein, a circuit for said restoring magnet having two paths, the continuity of each of which is controlled by both of said relays, a source of current at 65 the other end of the trunk line and switch- ing mechanism adapted in successive stages to open the trunk line and to interpose the last mentioned source of current therein.
23. In a telephone exchange system, the combination with an automatic switch and 70 restoring mechanism therefor, of a trunk line, a source of current at one end thereof, switching mechanism adapted to interpose said source of current in the trunk line, controlling means for said restoring mecha- 75 nism responsive to current in the trunk line, and means actuated in the movement of said switching mechanism adapted to change said controlling means to reverse the mode of control thereof over said restoring mecha- 80 nism, said trunk line having at the other end a source of current, a signal device and switching mechanism, said signal device being included in the trunk line and responsive to the first mentioned source of current, and 85 the last mentioned switching mechanism being adapted in successive stages to open said trunk line and to interpose therein the last mentioned source of current.
24. In a telephone exchange system, the combination of a trunk line closed at both ends, said trunk line having at one end an automatic switch controlling the continuity 90 of the circuit of a called telephone line, re- 95 storing mechanism for said switch, and a controlling device in the trunk line for said restoring mechanism, said trunk line having at the other end a manual switch controlling the continuity of the circuit of a calling tele- 100 phone line, an automatic switch controlling the continuity of the circuit of said trunk line, restoring mechanism for said automatic switch, a source of current and switching mechanism, said switching mechanism being 105 under the control of said manual switch and adapted to interpose said source of current in the trunk line to cause the operation of the controlling device in the trunk line and said switching mechanism having an ele- 110 ment controlling the operation of the re- storing mechanism of the last mentioned automatic switch.
25. In a telephone exchange system, the combination with an automatic switch, re- 115 storing mechanism therefor, a telephone line 120 the circuit of which is controlled by said automatic switch, a substation switch ar- ranged to close said telephone line during its use and a device in the circuit of the tele- 125 phone line controlled by flow of current therein, of a trunk line, a source of current at one end thereof, switching mechanism controlled by said device and adapted upon the opening of the substation switch to in- terpose said source of current in the trunk line, a signal device in the trunk line at the other end thereof responsive to said source of current, controlling means for said re- 130 storing mechanism responsive to current in the trunk line and means operating in the

actuation of said switching mechanism adapted to change said controlling means to reverse the mode of control thereof over said restoring mechanism.

5. 26. In a telephone exchange system, the combination with an automatic switch, restoring mechanism therefor, a telephone line, the circuit of which is controlled by said automatic switch, a substation switch arranged to close the telephone line during its use and a device in the circuit of the line controlled by a flow of current therein, of a trunk line, a source of current at one end thereof, switching mechanism under the control of said device adapted to include said source of current in the trunk line when the substation switch is open, controlling means for said restoring mechanism responsive to current in the trunk line, means operating in the actuation of said switching mechanism adapted to change said controlling means to reverse the mode of control thereof over said restoring mechanism, a source of current at the other end of the trunk line and switching mechanism adapted in successive stages to open the trunk line and to close it through the last mentioned source of current.
27. In a telephone exchange system, a pair of substation lines, a talking connection established from one of said lines to the other, an automatic switch through which the connection extends, a closed trunk line forming part of said connection physically disconnected from but inductively connected to said substation lines, a restoring mechanism for said automatic switch and means

for including a source of current in said closed trunk to effect the operation of said restoring mechanism.

28. In a telephone exchange system, automatic switching apparatus, a closed trunk line and a subscriber's line connected to said trunk line by said automatic switching apparatus, a second substation line physically disconnected from but inductively connected to said trunk line, restoring mechanism for said automatic switching apparatus, and means actuated upon opening the said second substation line for including a source of current in the trunk line to effect the operation of said restoring mechanism.

29. In a telephone exchange system, automatic switching apparatus, a closed trunk line and a substation line connected to said trunk line by said automatic switching apparatus, a second substation line physically disconnected from but inductively connected to said trunk line, restoring mechanism for said automatic switching apparatus, means actuated upon opening either substation line for including a source of current in the trunk line, and electromagnetic devices, one at each end of said trunk respectively responsive to the inclusion of current in said trunk at the opposite end thereof.

In witness whereof, I hereunto subscribe my name this seventh day of September A. D., 1909.

FRANK R. McBERTY.

Witnesses:

IRVING MACDONALD,
EDGAR F. BEAUBIEN.
